UNITED STATES PATENT OFFICE.

MATHIAS R. KONDOFF, OF ROCHESTER, NEW YORK, ASSIGNOR, BY MESNE ASSIGNMENTS, TO FI-BO-PAK COMPANY, OF PHILADELPHIA, PENNSYLVANIA, A CORPORATION OF DELAWARE.

BOX.

Application filed October 1, 1917. Serial No. 194,192.

To all whom it may concern:

Be it known that I, MATHIAS R. KONDOFF, a citizen of the United States, residing at Rochester, in the county of Monroe and State 5 of New York, have invented certain new and useful Improvements in Boxes, of which the following is a specification.

The object of this invention is to provide a box made up of two or more consecutive 10 sections placed one within the other.

This and other objects of the invention will be fully illustrated in the drawings, described in the specification and pointed out in the claims at the end thereof.

15 In the drawings,

Figure 1 illustrates one of the blanks used for the making of the section of my improved box.

Figure 2 illustrates another one of the 20 blanks used for the making of another section of my improved box.

Figure 3 is a perspective view of the inner and outer sections put together, with part of the outer section broken away.

25 Figure 4 illustrates a modification of the blank shown in Figure 1.

Figure 5 illustrates a modification of the blank shown in Figure 2.

Figure 6 illustrates a modification of the 30 blank shown in Figure 1.

Figure 7 is a perspective view partly broken away of a section made from the blank shown in Figure 5.

Figure 8 illustrates a blank used in making a reinforcement to be used between the 35 sections of any of my improved boxes.

Figure 9 is a perspective view of the blank shown in Figure 8 partially folded.

Figure 10 is a perspective view of two 40 boxes placed together, one box being inverted on the other.

Figure 11 is a perspective view of an alignment piece.

In the drawings like reference numerals 45 indicate like parts.

In the drawings reference numeral 1 indicates the blank shown in Figure 1 and reference numeral 2 indicates the blank shown in Figure 2. The blank shown in Figure 1 is 50 cut on the full lines 3, 4, 5 and 6 and is bent or folded on the dotted lines, on which lines it may or may not be scored. The part indicated by reference numeral 7 will form the bottom of the box. The reference numer-

als 8 and 9 indicate the side walls of the section and reference numerals 70 and 71 indicate the end walls of the section. The side walls and end walls will be first bent up so as to stand at right angles to the bottom 7 or nearly so. On each of the side wall members 55 8 and 9 are provided the corner pieces 10 and 11, 12 and 13 and on each of the end wall pieces 70 and 71 are provided the corner pieces 14, 15, 16 and 17. The corner pieces 60 of the side wall members lap the end walls 65 and the corner pieces of the end walls lap the side walls as is shown in perspective in Figure 3.

Each pair of corner pieces such as 10 and 14, 11 and 15, 12 and 16, 13 and 17 in the 70 blank shown in Figure 1 is formed by cutting the respective corner members on a diagonal line, thus adapting each corner piece (in the box section folded from said blank) to lap the wall member which is adjacent to the 75 wall member to which said corner piece is attached. In this manner the corner members connect the end and side wall members of their respective box section.

The end wall members 70 and 71 of the 80 blank shown in Figure 1 are provided with the extensions 18, 19, 20 and 21 which when folded overlap the corner sections 10 and 11, 12 and 13 and serve to lock them in place and also form pockets for the reception of 85 the flanges of the cover. The corner pieces 14, 15, 16 and 17 will hold themselves in place as shown in Figure 3 by the natural spring of the material from which the blank is cut or all the corner sections or any part 90 of them may be fastened in place by adhesives or by stapling.

In the blank shown in Figure 1, I have 95 shown two sets of corner pieces by the use of which the end and side wall members will be doubly fastened to each other and a double thickness of stock will be provided at each corner and on each side of each corner. I regard this as an important feature of my invention.

The blank 2 shown in Figure 2 will be 100 cut on the full line 22, 23, 24 and 25 and will be folded on the dotted line. In this blank 26 will form the bottom of the box. 27 and 28 will form the side walls of the box and 29 105 and 30 will form the end walls of the box.

The side walls 27 and 28 will first be bent up at approximately right angles to the

bottom 26, after which the end walls 29 and 30 will also be bent up at substantially right angles to the bottom of the box. The corner pieces 31, 32, 33 and 34 which are attached to the ends of the end walls 29 and 30 will then be bent over the side walls of the box. The side wall members 27 and 28 are provided with the extensions 35 and 36, 37 and 38 which when folded lap the corner sections 31, 32, 33 and 34 and serve to lock them in place and also form pockets for the reception of the flange into the cover. The corner pieces 31, 32, 33 and 34 may also be fastened in place by stapling or by adhesive.

It will be noted that when the extensions 18 and 20 of the blank shown in Figure 1 and the extensions 35 and 37 of the blank shown in Figure 2 (and the corresponding members of the other blanks shown) are folded down over the corner sections, they hold the corner sections in place and thereby serve to hold or lock all of the members of each box section. The corner pieces 14-15-16-17 of the blank shown in Figure 1 are held in position when the section made from this blank is set up, because the end wall members 70 and 71 of the blank are held or locked against the corner sections 10-11-12-13 by reason of the extensions 18 and 20 overlapping the same. The extensions 18 and 20 of the blank shown in Figure 1 and similar extensions on the other blanks like 35^a and 37^a of the blank shown in Figure 5 are therefore referred to as a "locking means" for their respective sections.

It will be seen that part of the members of each blank mentioned are locked and the only loose members are the extension pieces themselves. By "loose members" it will be understood that applicant refers to members which are not only free to move relatively to the other members but if such movement were continued other members of the section would be progressively freed or unlocked and the section could be collapsed. It is pointed out that the members 14-15-16-17 of the blank shown in Figure 1 are not "loose members" in this sense because though they are free to swing about their line of attachment said movement is limited and does not result in the unlocking of other parts of the section.

In the blank shown in Figure 6 the corner sections 10^b-11^b-12^b-13^b are secured together and held by the hooks 40 and 41 engaging with the slots 42 and 43. When this blank is folded into a box section the end walls 70^b and 71^b become the "loose members" of the section for the reasons as stated in preceding paragraph.

It will be understood that the blank 1 may be used to form either the inner or the outer section of the box and in either case

the blank shown in Figure 2 will form the other section of the box. In every case the inner section will be made slightly smaller than the outer section and the blanks will be cut to correspond. The difference in their dimensions will be determined by the thickness of the stock used.

The box is finished by inserting the inner section of the box in the outer section and pushing it down therein until the bottoms come together.

The blanks from which the sections are formed will preferably be coated on one side with an adhesive coating so that the coating will be on the members that are in contact when the sections are coated and brought together.

In Figure 4 I have shown a blank which corresponds to the blank shown in Figure 1 except that on each of the end wall members but one extension is provided forming in the folded section merely a locking device instead of a pocket and in Figure 5 I have shown a blank which corresponds to the blank shown in Figure 2 except that on each of the side wall members but one extension is provided forming in the folded section merely a locking device thereon instead of a pocket.

In describing the part as shown in Figures 4 and 5 like parts correspond to those shown in Figures 1 and 2 have been indicated by the same reference characters that have been used in describing the corresponding parts in Figures 1 and 2, the reference character "a" being added to the characters to distinguish the parts of Figures 4 and 5 from those of Figures 1 and 2.

In Figure 3 I have shown a perspective view of the finished box made by putting the inner and outer sections together in which part of the outer section is broken away.

In Figure 6 I have shown a modification of the blank which can be used either as an inner or an outer section in conjunction with any of the blanks shown in Figures 1, 2, 4 and 5.

In describing the parts shown in Figure 6 like parts corresponding to those shown in Figure 1 have been indicated by the same reference characters that have been used in describing the corresponding parts in Figure 1, the reference character "b" being added to the numerals to distinguish the parts of Figure 1 from those of Figure 6.

As shown in Figure 6 on the corner pieces 12^b and 13^b I have provided the locking hooks 40 and 41 and on the corner pieces 10^b and 11^b I have provided the slots 42 and 43 with which the hooks 40 and 41 engage for the purpose of fastening the corner pieces together in the folded section as is shown in Figure 7. As shown in Figure 7 the blank of Figure 6 is folded so as to be

used as the outer section of the box with the interlocking corner pieces outside and if it were to be used for the inner section of the box the interlocking corner pieces would 5 be folded inside of the box and within the end members.

In Figure 8 I have shown a blank that is to be used in making a reinforcement to be used between the sections of any of my 10 improved boxes. This blank has been numbered 45 and comprises the bottom member 46, side wall members 47 and 48, end wall members 49 and 50 and the corner members 51 and 52 and 53 and 54, all of which corner 15 members are attached to the end wall members. The parts are cut on the full lines and are folded on the dotted lines and may or may not be scored.

In Figure 9 I have shown the blank 46 20 partially folded for use between the sections in the finished box.

In Figure 10 I have shown two boxes made according to my invention, one of which is inverted on the other with a single 25 cover between them. The cover is placed on the upper box and this box is then inverted on the lower box and thus one cover is made to do for both boxes. The flanges of the cover will alternately engage in the 30 pockets or between the sections of the upper and lower boxes. The boxes will be fastened together by a single piece of adhesive tape 56 which will run around the meeting edges of the boxes.

35 In Figure 11 I have shown an alignment piece 60 which engages both the upper and lower box and serves to hold the two boxes in alignment.

The extensions 19 and 21, 36 and 38 may 40 be omitted as shown in Figures 4 and 5 and in which case no pocket would be formed, for the adhesive would fasten both sides of the remaining extensions to the wall members.

45 To avoid this an extra piece can be used as is indicated at 59 in Figure 4 which piece would be placed along the top edge of the box at points where pockets are desired, either between the folded sections after they 50 are brought together or attached to the blanks before it is folded. These pieces will be held in place by the adhesive coated on one of the sections.

It will be understood that the blanks 55 scribed in this application will each be coated on one side with an adhesive before folding and after being coated, each blank will be formed up into a section and the sections will be placed one within another with 60 an adhesive between the sections with the bottom members superimposed after which the layers are pressed together so as to make them adhere to each other closely.

I claim:

65 1. The combination in an open box of a

plurality of blanks each comprising end and side wall members and a bottom member and each forming a separate box section; each of said blanks having corner members between its end and side wall members, the corner 70 members of one blank being cut on a diagonal line to form corner pieces on each side of said line, one of said corner pieces being attached to each of the ends of the side and end wall members in said blank, 75 and in the section formed therefrom said corner pieces being adapted to lap the adjacent wall members to form a double thickness at each of the corners and on both sides thereof.

2. The combination in an open box of a plurality of blanks each comprising end and side wall members and a bottom member and each forming a separate box section; each of said blanks having corner members between its end and side wall members, the corner members of one blank being cut on a diagonal line to form corner pieces on each side of said line, one of said corner pieces being attached to each of the ends of the side 90 and end wall members in said blank, and in the section formed therefrom said corner pieces being adapted to lap the adjacent wall members to form a double thickness at each of the corners and on both sides thereof; and adhesive between the layers of the box and the layers of the combined sections being pressed closely together to finish the box.

3. The combination in an open box of a 100 plurality of blanks each comprising end and side wall members and a bottom member and each forming a separate box section; one of said blanks having corner members between its end and side wall members, each of said 105 corner members being cut on a diagonal line to form corner pieces on each side of said line, one of said corner pieces being attached to each of the ends of the side and end wall members in said blank, and in the section formed therefrom said corner pieces being adapted to lap the adjacent wall members to form a double thickness at each of the corners and on both sides thereof; and a reinforcement placed between two of said box 110 sections and held in place thereby; and adhesive between the layers of the box and the layers of the combined sections being pressed closely together to finish the box.

4. The combination in an open box of a 120 plurality of blanks each comprising end and side wall members and a bottom member and each forming a separate box section; one of said blanks having corner members between its end and side wall members, each of said 125 corner members being cut on a diagonal line to form corner pieces on each side of said line, one of said corner pieces being attached to each of the ends of the side and end wall members in said blank, and in the section 130

formed therefrom said corner pieces being adapted to lap the adjacent wall members to form a double thickness at each of the corners and on both sides thereof; and extension pieces attached to one pair of wall members in two of said box sections and folded to form cover flange pockets at the top of the box; and adhesive between the layers of the box and the layers of the combined sections 10 being pressed closely together to finish the box.

5. An open box comprising a plurality of blanks forming separate box sections each having loose members, each of said blanks 15 comprising members to form end and side walls and a bottom when folded into a box section; one of said blanks having corner members between its end and side wall members, each of said corner members being cut 20 on a diagonal line to form corner pieces on each side of said line, one of said corner pieces being attached to each of the ends of the side and end wall members in said blank, and in the section formed therefrom 25 said corner piece being adapted to lap the adjacent wall members to form a double thickness at each of the corners and on both sides thereof; two of said box sections having locking means adapted to hold part of the 30 members of said sections in box form; all of said box sections being assembled one within another so that the bottom members superimpose and the loose members of all the sections are held in place; and adhesive between the layers of the box and the layers of the combined sections being pressed closely together to finish the box.

35. An open box comprising a plurality of blanks forming separate box sections each having loose members, each of said blanks comprising members to form end and side walls and a bottom when folded into a box 40 section; one of said blanks having corner members between its end and side wall members, each of said corner members being cut on a diagonal line to form corner pieces on each side of said line, one of said 45 corner pieces being attached to each of the ends of the side and end wall members in said blank, and in the section formed therefrom said corner pieces being adapted to lap the adjacent wall members to form a 50 double thickness at each of the corners and on both sides thereof; two of said box sections having locking means adapted to hold part of the members of said sections in box form; all of said box sections being assembled one within another so that the bottom 55 members superimpose and the loose members of all the sections are held in place; and a reinforcement placed between two of said box sections and held in place thereby.

60. 7. An open box comprising a plurality of blanks forming separate box sections each having loose members, each of said blanks comprising members to form end and side walls and a bottom when folded into a box 65 section; one of said blanks having corner

members between its end and side wall members, each of said corner members being cut on a diagonal line to form corner pieces on each side of said line, one of said corner pieces being attached to each of the ends of the side and end wall members in said blank, and in the section formed therefrom said corner pieces being adapted to lap the adjacent wall members to form a double thickness at each of the corners and on both sides 70 thereof; two of said box sections having locking means adapted to hold part of the members of said sections in box form; all of said box sections being assembled one within another so that the bottom members superimpose and the loose members of all the sections are held in place; and adhesive between the layers of the box and the layers of the combined sections being pressed closely together to finish the box.

85. 8. An open box comprising a plurality of blanks forming separate box sections each having loose members, each of said blanks comprising members to form end and side walls and a bottom when folded into a box 90 section; one of said blanks having corner members between its end and side wall members, each of said corner members being cut on a diagonal line to form corner pieces on each side of said line, one of said corner pieces being attached to each of the ends of the side and end wall members in said blank, and in the section formed therefrom said corner pieces being adapted to lap the adjacent wall members to form a double thickness at each 95 of the corners and on both sides thereof; two of said box sections having locking means adapted to hold part of the members of said sections in box form; all of said box sections being assembled one within another so that the bottom members superimpose and the loose members of all the sections are held in place; and extension pieces attached to one 100 pair of wall members in two of said box sections and folded to form cover flange pockets at the top of the box; and adhesive between the layers of the box and the layers of the combined sections being pressed closely together to finish the box.

105. 9. An open box comprising two series of 115 members adapted to form a plurality of layers on the sides, ends and bottom of the box, each series of members having locking means adapted to lock part of the members of each series in box form and leave part of the 120 members loose; one of said series having corner members between the end and side wall members, each of said corner members being cut on a diagonal line to form corner pieces on each side of said line, one of said 125 corner pieces being attached to each of the ends of the side and end wall members in said series, and in the section formed therefrom said corner pieces being adapted to lap the adjacent wall members to form a double 130

thickness at each of the corners and on both sides thereof, the loose members of both series being held in place when the bottom members are superimposed.

5 10. An open box comprising a plurality of separate box sections having bottom and end and side walls, adhesive on the surfaces in contact between the sections, a strip placed between said sections to leave an open pocket at the top edge of the box.

10 11. A package comprising two open boxes one of which is inverted on the other with their tops placed together and a single cover between said tops, flanges on said cover,

pockets formed in the walls of each of said boxes, part of the flanges being bent up into the pockets of the one box and part of said flanges being bent down into the pockets of the other box, the boxes being fastened together at their meeting edges.

20 12. A package comprising two open boxes one of which is inverted on the other with their tops placed together, pockets formed in the walls of each of said boxes, locking pieces engaging said pockets and holding said boxes in alignment.

In testimony whereof I affix my signature.
MATHIAS R. KONDOLF.
